UNITED STATES PATENT OFFICE.

PERREY MILTON DURDEN, OF LUFKIN, TEXAS.

WASHBOARD.

1,207,516.

Specification of Letters Patent. Patented Dec. 5, 1916.

Application filed April 5, 1916. Serial No. 89,942.

To all whom it may concern:

Be it known that I, PERREY M. DURDEN, a citizen of the United States, residing at Lufkin, in the county of Angelina and State of Texas, have invented new and useful Improvements in Washboards, of which the following is a specification.

This invention relates to a washboard wherein provision is made for automatically moving, step by step, a cake of soap inclosed in a housing on the rubbing board temporarily into contact at pre-determined intervals with the articles being washed, thereby enabling the soap to be used economically and insuring the proper quantity of soap being diffused over the rubbing surface of the rubbing board.

Another object of the invention is to provide mechanism for moving the soap, step by step, into contact with the articles being washed, which may be operated by the pressure exerted through the rubbing action upon a rubbing board associated with the device.

A still further object of the invention is to provide a washboard of the class described with a rubbing board mounted to oscillate within a supporting frame in such a manner that oscillatory movement of the rubbing board will operate the soap moving mechanism.

Another object of the invention is to provide a supporting frame with an oscillatory rubbing board and having adjustably mounted thereon a member by means of which the frequency with which the cake of soap is brought into contact with the articles upon the rubbing board may be increased or decreased as desired.

With these and other objects in view, the invention resides in the novel combination and arrangement of parts, which will be hereinafter described and particularly pointed out in the claims.

The preferred embodiment of the invention has been illustrated in the accompanying drawing, although no restriction is necessarily made to the precise details of construction therein shown, as changes, alterations, and modifications within the scope of the claims may be resorted to when desired.

Like characters of reference denote corresponding parts throughout the several views in the drawings, in which:

Figure 1 is a front elevation of a washboard constructed in accordance with the

invention. Fig. 2 is a rear elevation, parts being shown broken away to better illustrate the mechanism for moving the soap into contact with the articles upon the rubbing board. Fig. 3 is a vertical longitudinal sectional view on the line 3—3 of Fig. 2. Fig. 4 is a view similar to Fig. 3 taken on the line 4—4 of Fig. 2 and showing a portion of the soap moving mechanism in a different position. Fig. 5 is a horizontal transverse sectional view on the line 5—5 of Fig. 2 looking in the direction indicated by the arrows. Fig. 6 is a fragmentary transverse sectional view on the line 6—6 of Fig. 2 to more clearly illustrate the ratchet mechanism for operating the soap moving means.

Referring now to the drawings in detail, the numeral 1 designates a U-shaped supporting frame having spaced parallel arms 2, each of which is provided between its ends with a bearing opening 3, said arms being connected by a top bar 4 and a cross-piece 5 arranged adjacent the free ends of the arms 2. A bracket 6 is secured to and extends below the top bar 4 adjacent one of the arms 2 and is provided near its free end with a threaded opening 7.

A rubbing board frame 8 is provided which is rectangular in shape and comprises a top bar 9, a bottom bar 10, and side bars 11, each of which is provided between its ends with a trunnion 12 removably mounted in one of the bearing openings 3 in an arm 2 on the supporting frame 1, said rubbing board frame being provided at spaced intervals with lugs 13, each of which has an aperture 14 therein. A corrugated rubbing board 14' is mounted within the rubbing board frame 8 and removably secured to the lugs 13 in any suitable manner, said board being formed from any suitable material such as glass, galvanized iron, or the like, with the corrugations thereon arranged in any manner found desirable. The rubbing board 14' is provided with a centrally arranged and transversely extending opening 15 for a purpose which will be presently described.

A bar 16 extends transversely between the side bars 11 adjacent the trunnions 12 and has mounted thereon a soap housing 17, the top wall of which is provided with spaced and longitudinally extending slots 18, said wall forming at one end of the housing, a spring latch member 19 engageable with the

bottom wall of the housing 17, while the other end of the housing extends within the opening 15 in the rubbing board 14. A follower 20 is mounted to slide in the soap housing 17 and is provided in its upper face with recesses 21 registering with the slots 18 in the top wall of said housing. A supporting leg 22 is formed integral with the bar 16 and extends downwardly therefrom below the soap housing 17 and has its free end connected with the bottom bar 10 of the rubbing board frame 8.

A link 23 has formed therein between its ends a longitudinally extending opening 24, said link having an end pivotally connected with ears 25 on the top bar 9 of the rubbing board frame 8 and its lower end formed with spaced fingers 26, each of which passes through one of the slots 18 in the top wall of the soap housing 17 and has an end loosely received in a recess in the follower 20, so that as said link is turned about its pivotal connection with the ears 25 in a manner which will be presently described, the follower will be slid in the soap housing 17 toward the rubbing board 14'.

Arms 27 extend inwardly from the side bars 11 of the rubbing board frame adjacent the top bar 9 and each arm has formed therein a bearing opening 28 in which is mounted to turn the reduced end of a transversely extending shaft 29, said shaft being provided between its ends with a cam-wheel 30. The cam-wheel 30 is provided with a pair of curved faces 30' so arranged with relation to the link 23 that during the rotation of the shaft 29, said faces are successively brought into contact with the link 23 below the opening 24 therein, thus causing the link to move the follower in the soap housing 17 toward the rubbing board 14'. As the follower moves toward the rubbing board 14' the curved face on the cam-wheel is raised above the lower edge of the opening 24 so that due to the inclined position of the board and the weight of the soap on the follower, the follower is moved by gravity toward the latch member 19, or what might be termed its normal position and when in such position a portion of the cam-wheel is received in the opening 24 in the link 23. The shaft 29 has mounted thereon near one end a worm-wheel 31 meshing with a vertically extending worm-shaft 32 having an end journaled in one of the arms 27 adjacent the wheel 31 and its other end received in a bearing opening in a lug on the top bar 9 of the rubbing board frame 8.

60 A ratchet wheel 33 is fixed to the shaft 32 beneath the top bar 9 of the rubbing frame and has engaged therewith a spring pressed pawl 34 pivotally connected with the bar 9. A second pawl 35 is pivotally connected with an ear 37 on one of the arms

2 of the supporting frame 1 and has one end held in engagement with the ratchet wheel 33 by a spring 38 interposed between the pawl and the arm on the supporting frame which carries the ear to which the pawl is connected. The shaft 32 has secured to the end thereof which extends above the top bar 9 an operating wheel 39 which may be manually turned to cause the shaft 32 to impart turning movement to the shaft 29 and cause the cam-wheel 30 to move the link 23.

Adjustably connected with the top bar 9 of the rubbing frame is an ear 40 adapted to contact with a screw 41 threadedly engaged with the opening 7 in the bracket 6 to limit the swinging movement of the rubbing board frame when pressure is applied thereto during the washing operation, such movement advancing the soap disposed within the housing 17, step by step, into contact with the articles being rubbed upon the rubbing board.

When it is desired to use the board, the same is disposed within a tub in the usual inclined position and a cake of soap is positioned within the housing 17 through the opening 15 in the rubbing board. The screw 41 is adjusted within the opening 7 in the bracket 6 with relation to the ear 40 until rubbing movement upon the rubbing board will only impart a slight oscillatory movement to the board and frame connected therewith. The operating wheel 39 may now be turned to rotate the shaft 29 to cause a curved face 30' on the cam-wheel to contact with the link 23 below the opening 24 therein and advance the follower 20 within the housing 17 toward the rubbing board 14' sufficiently far to cause a face on the soap to lie flush with the front face of the rubbing board. The articles to be washed may now be rubbed over the soap and then over the rubbing board such rubbing action imparting rocking movement to the rubbing board supporting frame and causing the pawl 35 to turn the shaft 32 by means of the ratchet wheel 33, such turning movement of the shaft 32 rotating the shaft 29 through the connection of the wheel 31 with the shaft 32, thereby releasing the said curved face 30' on the wheel 30 from engagement with the link 23 and allowing the follower and soap to move within the housing 17 toward the latch member 19 under the influence of gravity.

It will, of course, be understood that the continued rubbing movement on the corrugated face of the rubbing board will cause the shaft 29 to be still further rotated through the mechanism described thus bringing the other curved face 30' on the wheel 30 into contact with the link 23 and again advancing the soap, step by step, into contact with the articles being cleaned. As

the soap wears away, the screw 41 is adjusted to increase the rocking movement of the rubbing board, so that the distance that the ratchet wheel 33 is turned by the pawl 39 is increased thus increasing the frequency with which the soap is temporarily moved into contact with the articles being cleaned.

From the foregoing statements, taken in connection with the accompanying drawing, it is at once apparent that a washboard has been provided which is strong and durable, and highly efficient in use.

Having thus described the invention, what is claimed as new, is:

1. A washboard comprising a supporting frame, a rubbing board mounted within said frame to turn when articles are rubbed thereon, a housing carried by the supporting frame and received in an opening in the rubbing board, a follower within said housing, a link connected with the rubbing board for swinging movement, and mechanism carried by the supporting frame and rubbing board and operable through the turning movement of said board to impart swinging movement to the link.

2. A washboard comprising a supporting frame, a rubbing board mounted within said frame to turn when articles are rubbed thereon, a housing having an end received in an opening in the rubbing board and provided with a slotted top wall, a follower loosely mounted in the housing, a link connected with the rubbing board for swinging movement, spaced fingers on said link passing through the slotted top wall of the housing and engaged with the follower, and mechanism carried by the supporting frame and the rubbing board and operable through the turning movement of the rubbing board to impart movement to the follower within the housing.

3. A washboard comprising a supporting frame, a rubbing board frame pivotally connected with the supporting frame, a rubbing board carried by the rubbing board frame to impart swinging movement thereto when articles are rubbed on the rubbing board, a soap housing having an end received in an opening in the rubbing board, a follower disposed within said housing,

means for imparting sliding movement to the follower, a shaft carried by the rubbing board frame and provided with a cam-wheel, and mechanism connected with the supporting frame and rubbing board frame and operable through the rocking movement of the rubbing board frame to rotate said shaft and cause the cam-wheel thereon to contact with said means.

4. A washboard comprising a supporting frame, a rubbing board frame pivotally connected with the supporting frame, a rubbing board removably connected with the last mentioned frame and adapted to impart rocking movement to the rubbing board frame when articles are rubbed on the rubbing board, a housing carried by the rubbing board frame and having an end received in an opening in the rubbing board, a follower in said housing, means for imparting sliding movement to the follower including a shaft having a worm-wheel thereon, and mechanism carried by the supporting frame and rubbing board frame and operable through the rocking movement of the rubbing board frame to rotate said worm-wheel.

5. A washboard comprising a supporting frame, a rubbing board frame mounted to turn within said supporting frame, a rubbing board having a transversely extending slot therein and connected with the rubbing board frame to impart swinging movement thereto when articles are rubbed thereon, a housing carried by the rubbing board frame and having an end received in the opening in the rubbing board, said housing being adapted to receive a cake of soap, means for imparting movement to the soap within the housing including a worm-shaft having a ratchet wheel thereon, and a spring pressed pawl adapted to be operably engaged with the ratchet wheel by the turning movement of the rubbing board supporting frame.

In testimony whereof I affix my signature in presence of two witnesses.
